(57) **CLAIM**

The ornamental design for a power strip, as shown and described.

DESCRIPTION

FIG. 1 is a perspective view of a power strip showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

In FIGS. 1, 2, 3, 4, 7 and 8 the dash-dot-dash broken line is for the purpose of showing the boundary of the claim. Throughout the drawings, the even dash-dash broken lines are for the purpose of illustrating environment only and form no part of the claimed design.

1 Claim, 5 Drawing Sheets
